UNITED STATES PATENT OFFICE.

WESLEY DEUETTE TYLER, OF PLAQUEMINE, LOUISIANA.

MOSS-CLEANING APPARATUS.

Application filed June 12, 1924. Serial No. 719,686.

To all whom it may concern:

Be it known that I, WESLEY D. TYLER, a citizen of the United States, and resident of Plaquemine, in the parish of Iberville and State of Louisiana, have invented certain new and useful Improvements in Moss-Cleaning Apparatus, of which the following is a specification.

My invention relates to improvements in moss cleaning machinery and it consists of the constructions, combinations and arrangements herein described and claimed.

An object of the invention is to provide a machine adapted particularly for the purpose of cleaning moss, special use being made of a primary and secondary cleaning unit or machinery so separated that the action of gravity plays a part in the action on the moss.

Another object of the invention is to provide a moss cleaning apparatus in which not only the sticks and dirt are removed from the moss but in which there is such an arrangement of blowers which act upon the moss to dust it.

Another object of the invention is to provide a novel method of treating moss for preparation into a clean and marketable product.

Other objects and advantages will appear in the following specification, reference being had to the accompanying drawings, in which—

Figure 1 is a diagrammatic section illustrating the general lay out of the moss cleaning apparatus.

Figure 2 is a sectional view of the primary moss cleaner.

Figure 3 is a cross section of the primary moss cleaner taken substantially on the line 3—3 of Figure 2.

Figure 4 is a detail perspective view, partly in section, showing the toothed bar or plate which confronts the cylinder in Figure 2.

Figure 5 is a detail cross section on the line 5—5 of Figure 2 illustrating the mounting of the adjustable bottom plate.

Figure 6 is a detail side elevation of the

belt tightener used in connection with the primary cleaner.

Figure 7 is a section on the line 7—7 of Figure 6.

Figure 8 is a longitudinal section of the secondary moss cleaner.

Figure 9 is a section on the line 9—9 of Figure 8.

Figure 10 is a detail view of a portion of the drum in Figure 8, illustrating the staggered arrangement of the teeth.

Figure 11 is a detail perspective view of one of the teeth.

Figure 12 is a detail perspective view of a portion of the brush cylinder of the secondary cleaner, illustrating the setting of the bristles.

Figure 13 is a detail side elevation, partly in section, of the dust extractor at which the clean moss is finally discharged.

Figure 14 is a view similar to Figure 13 illustrating the action upon opening the air valve in the blower pipe.

Figure 15 is a detail side elevation of the air valve.

Figure 16 is a plan view thereof.

Figure 17 is a detail plan view illustrating the arrangement of teeth on the primary cleaner drum.

It may be stated, by way of preface, that at present there is no machinery especially designed and adapted for the particular purpose of picking or cleaning moss. This is largely due to the fact that the industry of gathering and using moss is a minor one and confined to quite limited territory.

There are known machines for ginning purposes, for example cotton, but an endeavor to use a cotton gin for the purpose of combing and cleaning moss has met with failure. This is largely due to the fact that the moss fiber is quite long, and when freshly gathered is very dirty, being full of sticks, dirt and small limbs from the trees on which it grows.

It has therefore become necessary to not only design a particular type of gin which will effectively comb and clean the moss but also design a plant or system in which the moss can be treated ac-

cording to a predetermined process. The action of gravity plays an important part in the apparatus, as the reader will understand in a moment.

- 5 In carrying out my invention, use is made of a building B which has ground, first and second floors 1, 2 and 3 respectively providing as many rooms as there are floors for the purpose of holding the various machines. 10 The process of treating the moss commences at the primary cleaner 4, from which it passes to the secondary cleaner 5, discharging into what may be designated a bin 6 and finally entering the dust extractor 15 7. The moss is made to travel a circuitous route so that all of the various machines may be reached and that the action thereon may be thorough.

Consider first the primary moss cleaner 4 on the top floor 3. The moss just as it is gathered is dumped upon the feed table 8 (Fig. 2) from which it is drawn into the primary cleaner by a pair of solid iron corrugated feed rolls 9 and 10. One of 20 these feed rolls carries a gear 11 which is driven by a pinion 12 on a countershaft 13 which is mounted in suitable bearings 14 (Fig. 3) upon the frame of the primary cleaner. The countershaft carries a pulley 25 15 which is driven by a belt 16 from the pulley 17 on the main shaft 18 of the drum 19. The main shaft is journaled in bearings 20 on the frame of the machine. The belt runs over an idler 21 (Fig. 6) and also 30 35 a tightener pulley 22, the latter being for the purpose of keeping the belt under proper tension.

A spring 23 (Fig. 6) presses down upon a block 24 which carries a stub shaft 25 upon which the pulley 22 rotates. The block slides in a slot 26 which is also occupied by the spring. A screw 27 is arranged to bear upon the washer 28 ahead of the spring so that the tension of the spring may 40 45 be adjusted according to requirements. A suitably fixed stub shaft 29 carries the idler 21. Both pulleys are supported by a bracket 30 which is fixed either upon the floor 3 (Fig. 2) or upon any available part of the cleaner frame.

This frame comprises the horizontal rails 31. These may consist either of channels as shown or members of other desired structure. The rails are supported by legs 55 32 which may be of angle iron. The legs 32 at the entrance end of the cleaner are specially formed to accommodate the bearing block 33 in which the trunnions 34 of the feed rolls 9 and 10 are journaled.

60 That feed roll opposite to the one which is positively driven is pressed toward the driven feed roll by means of springs 35 which are kept under tension by screws 36 which are accessible from above in the present instance. Of necessity the idle feed roll

is driven by virtue of the corrugations on the surfaces of both rolls.

Teeth 37 protrude from the drum 19 either in radial position or at a slight angle from the radial position as illustrated 70 in Figure 2. These teeth are of steel and have blunt points. They are also slightly tapered. They are staggered as shown in Figure 17. The teeth are approximately two inches apart in each row reading along 75 the axis of the drum, and one-half inch apart when following the circumference of the drum. The resulting staggered arrangement can be understood without difficulty.

A plate 38 (Fig. 4) confronting the drum 19 (Fig. 2) carries teeth or spikes 39 which oppose the teeth 37 of the drum. The stationary and movable teeth 39 and 37 respectively perform a combing action on the moss as it is fed into the throat 40 by the corrugated feed roll. The plate 38 is adjustable 85 in respect to the drum, and for this purpose carries brackets 41 which are secured in the slotted portions 42 (Fig. 4) of the frame channels 31 by bolts 43. Upon unloosening 90 the nuts on the bolts the plate 38 may be bodily moved in respect to the drum.

A bottom plate 44 controls the separation of sticks, etc., from the good moss. This plate has a thickened leading edge 45. The plate has racks 46 which are engaged by pinions 47 on a shaft 48 which has a hand wheel 49 (Fig. 5) for the purpose of turning the shaft and adjusting the bottom plate back and forth in the guides 50. In practice it is found that the leading edge 45 may be set at such a position that a substantially clean separation of the moss from the refuse can be made.

The moss, being lighter, discharges into 105 the passage 51 which leads into the screen outlet 52. The refuse, being heavier than the moss, discharges at a more decided tangent to the drum and enters a chute 53 defined by the bottom plate and the bottom screen 54 of the outlet 52. The refuse slides down the chute and falls upon the dirt and trash conveyor 55 which discharges at a suitable point outside of the building B. 115

An exhaust fan 56 draws the liberated moss against the top curved screen 57 of the outlet 52 and thus attracts a great portion of dust. The fan has communication with the outlet 52 through a dust tunnel 58. The fan discharges into a pipe 59 which has communication with the common dust outlet conduit 60 which also discharges outside of the building. 120

That portion 61 of the outlet 52 in continuation of the curved screen 57 is composed of solid sheet metal which extends close to the end of the bottom screen 54, but sufficiently far therefrom to leave an ample passage for the moss immediately 130

above the feed table 52 of the secondary cleaner 5. Before describing the secondary cleaner 5 it must be pointed out that the primary cleaner 4 is suitably enclosed in 5 a casing of sheet metal which provides sides 63, ends 64 (Fig. 2) and a cover 65. The latter is hinged at 66 so that access may be had to the interior.

Consider now the secondary cleaner 5. 10 This machine is essentially the same as the primary cleaner 4, although it involves some differences in construction it performs the function of cleaning and combing the moss.

The feed table in this instance has a 15 slatted conveyor 67 running over suitably driven rollers 68, which feeds the moss to a pair of spiked rolls 69 and 70. The feed rolls are of iron and the sets of inclined teeth 71 and 72 mesh in such a manner that 20 the turning of one roll turns the other in the opposite direction.

A gear 73 on one of the rolls is driven by a pinion 74 on a countershaft 75. The countershaft carries a pulley 76 which is 25 driven by a belt 77 from a pulley 78 on the shaft 79 of the drum 80. The belt passes over an idler 81 and a tightener pulley 82 which is much on the order of the tightener in Figure 6.

30 Springs 83 hold the feed rolls 69 and 70 together. The tension of the springs is adjustable by screws 84. These are carried by upright parts 85 forming part of the frame. The frame includes the horizontal rails 86 and the various legs 87. The springs bear 35 on blocks 88 in which the trunnions of the upper roll are journaled. The lower roll has similar trunnions journaled in bearings 89.

40 Teeth 90 protruding from the drum 80 co-operate with teeth 91 extending inward from the cover 92 of the gin casing to comb the moss as it travels through the passage between the drum and cover on the way to 45 the brush casing 93. An entrance plate 94 defines a throat 95 at the beginning of the passage mentioned. The under surface of this plate is curved inwardly so as to insure 50 guiding the moss toward the teeth of the drum.

The distance between the teeth 90 and 91 may be adjusted by means of screws 96 carried by lugs 97 on the cover 92. These 55 screws bear against fixed parts of the frame and by turning the screws up or down adjustment of the teeth 91 in respect to the other teeth will result. This is due to the fact that the cover 92 is hinged at 98. Thus the teeth 90 and 91 stand at angles to the perpendicular of the drum and cover. The drum rotates in the direction of the arrow.

60 A large pulley 99 on the shaft 79 beside the drum 80 drives the brush cylinder 100 by means of a belt 101 which passes over an idler 102 and a relatively small pulley 103

on the shaft 104 of the brush cylinder. The ratios of the various pulleys cause the brush cylinder 100 to revolve at a high speed. The arrow indicates the direction of rotation. Bearings 105 support the cylinder 70 shaft. These are carried by the horizontal channels 86 of the frame. The idler 102 is mounted upon an arm 106 which in turn is mounted in such a way that the belt 101 may be kept tight. 75

The ribs 107 of the brush cylinder consist of double rows of steel brush wire as shown in Figure 12. Rotation of the drum 80 and brush cylinder 100 in the directions indicated cause a further separation of refuse 80 from the moss, the former discharging into an outlet 108 which has communication with the chute 53 (Fig. 1) the latter entering the passage 109 which communicates with the bin 6 (Fig. 1) mentioned before. 85

A bottom plate 110 defines part of this passage. A rack 111 and a pinion 112 on the shaft 113 permit such adjustment of the leading edge of the bottom plate as will produce a clean separation of refuse from the 90 moss. In order to prevent the moss from reaching the brushing cylinder too soon, a guard plate 114 is situated in the space between the drum and cylinder in a position approximately opposite that of the bottom plate 110. 95

A guide 115 provides the support in which the bottom plate 110 is slideable when the shaft 113 is turned. The large common outlet conduit 60, mentioned before in connection with Figure 1, is of rather large area in its approximately medial portion, this for the purpose of accommodating a screen 116 against which the moss is discharged from the passage 109. The action 100 of the exhaust fan 56 and of another fan 117 create a tendency toward the exhaustion of air from the conduit in the region of the screen 116, with the result that more dust and objectionable fine particles are separated from the moss as it is thrown against the screen. 105

Any heavy particles passing through the screen 116 and failing to pass out with the air in the conduit 60 will fall to the bottom 110 of the conduit and slide down to the trash conveyor 55. It is to be observed that the screen 116 extends all the way round to the bottom of that which is known as the bin 6 to provide every opportunity for dirt to fall 115 from the moss. 120

A screen 119 extends from a point adjacent to the passage 108 where it is fastened upon a bracket 120, to a plate 121 which extends up under the lowest feed roll 70 as clearly shown in Figure 8. This so called screen is in reality a grating consisting of rods of suitable material arranged crosswise to provide interstices of suitable dimension. The casing of the brush cylinder has a hinged 125 130

cover 122 which may be opened for an inspection of the interior.

A tube 123 conducts the now clean moss from the bin to the dust extractor 7 (Figs. 5 1 and 13). It is the suction of the fan 117 that draws the moss up into the tube. The conduit 124 leading from the fan 117 begins at a hood 125 which is so situated in respect to the dust extractor as to cover the 10 screen 126. The moss strikes the screen 126 with considerable force and the last of any dust that it might contain is drawn off into the conduit 124 and is discharged into a pipe 127 that leads to the common outlet 15 conduit 60.

The dust extractor comprises a casing 128 which has bottom doors 129 held closed by the suction of the fan 117 when the air valve 130 is closed. This valve is situated in the 20 conduit 124. The valve includes a plate 131 which may be swung on the pivot 132 against the tension of a spring 133 to expose the opening 134 and admit air to the fan. The dust extractor being thus short 25 circuited will immediately discharge its contents of moss by virtue of the doors 129 opening (Fig. 14) due to the absence of suction to keep them closed. Upon permitting the valve plate 131 to close suction is again 30 created in the tube 123 and cylinder 128 causing the lifting of moss from the bin 6 and the accumulation thereof in the dust extractor 7. The doors 129 are caused to close by suction when the valve 130 is closed.

35 Means for driving the various ginning machines and suction fans is not shown in the drawings. The manner of erecting a common line shaft and driving a number of separate machines therefrom is quite commonly known and may be adopted in this 40 particular instance. All that is required is a suitably driven shaft or as many shafts as may be needed, together with suitable pulleys and belting.

45 In practice the dust extractor casing 128 will not discharge upon the floor 3 as seemingly indicated in the drawings (Fig. 1) for example. The moss is suitably conducted to a baling press in which it is 50 formed into bales or bundles ready for shipment. The baling press is not illustrated in the drawing inasmuch as it has no direct bearing on either the apparatus or the process.

55 The operation will be readily understood from the following additional description. The moss is conveyed to the upper floor 3 of the building B in any suitable manner, where it is supplied in suitable quantities to 60 the feeding table 8 of the primary cleaner 4. In its freshly harvested state the moss is in a very dirty condition, containing sticks and branches of the trees from which it is separated as well as considerable dirt.

65 It is the purpose of the apparatus to

thoroughly clean the moss and separate it from the refuse so that the resulting product is immediately ready to be baled and shipped to its destination. The action of the primary cleaner 4 is to cause a preliminary 70 separation of the sticks, etc. from the moss, one falling into the chute 53 (Fig. 1) the other being expelled by centrifugal force into the screened outlet 52. It is to be observed that the outlets of the gins 4 and 5, 75 both as to moss and refuse, are directed downward. The refuse upon striking the chute 53 falls down until the trash conveyor 55 is reached. The moss also moves in a downward direction, and it is therefore to 80 be seen that the action of gravity plays no small part in conducting the process of cleaning the moss. The moss discharged by the primary cleaner 4 falls upon the feed conveyor 67 of the secondary gin 5. This is 85 a finishing cleaner in that the separation of the moss from any remaining refuse and the proper combing of the moss is here completed. The latter function is largely performed by the brush cylinder 100 (Fig. 8) 90 which also sweeps the moss into the passage which leads to the bin 6 (Fig. 1).

Two blowers or exhaust fans are in continuous operation. Both function to remove as much dirt and dust as possible, the latter 95 also functioning to lift the moss from the bin 6 through a pipe 123 into the dust extractor 7. Upon striking the screen 126 the moss will scatter or separate so that any remaining particles of dust may readily be 100 drawn through by the fan 117 and expelled into the common outlet 60 with which the pipe 59 of the fan 56 also communicates. As long as the valve 130 remains closed moss will be drawn up through the pipe 123 and 105 discharged into the casing 128 because the doors 129 will be held closed due to the suction which is considerable. However, upon moving the valve plate 131 so as to expose the opening 134 the dust extractor will be 110 short circuited, and the resultant diminution of suction will permit the gates 129 to open by gravity and expel the contents either upon the floor or elsewhere.

115 The process consists of primarily and secondarily cleaning the moss, causing the moss to take one path and the refuse another. The moss is subjected to currents of air for the purpose of lifting out dirt and dust and finally discharging the moss into a casing 120 which is periodically emptied.

125 While the construction and arrangement of the improved moss cleaning apparatus as herein described and claimed is that of a generally preferred form, obviously, modifications and adaptations may be made without departing from the spirit of the invention or the scope of the claims.

I claim:—

1. Apparatus of the character described 130

- comprising a plurality of cleaning machines for separating the refuse from moss, means associated with each machine against which the moss is discharged, means including exhaust fans for then withdrawing dust from the moss, means upon which the refuse falls from each machine and slides by gravity to a common point, and means operating beneath said point for conveying the refuse to a place of discharge. 5
2. Apparatus of the character described comprising a plurality of cleaners situated in planes above each other, means operating inside of each cleaner to separate the refuse from moss, means including a chute located in common with the cleaner and upon which the refuse slides by gravity to a common point, means operating at said point to convey the refuse to a place of discharge, means including a screen associated with each cleaner against which the moss is discharged and from which it falls by gravity, air tunnels in which each screen is situated having communication with a common outlet conduit, and means including an exhaust fan discharging into said outlet and communicating with the tunnels to withdraw dust from the moss at said screens. 10
3. Apparatus of the character described comprising a plurality of cleaners situated in planes above each other, means including a screen associated with each cleaner against which moss is discharged and spread after separation from the refuse, a common chute into which the refuse falls and gravitates to a common point, a bottom screen associated with the uppermost cleaner preventing the moss from falling into the chute yet permitting dirt to fall through said screen conducting the moss to the intake of the cleaner next below, and means associated with the screens against which the moss is discharged for withdrawing dust. 15
4. Apparatus of the character described comprising a plurality of cleaners situated in planes above each other, means including a screen associated with each cleaner against which moss is discharged and spread after separation from the refuse, a common chute into which the refuse falls and gravitates to a common point, a bottom screen associated with the discharge screen of the lowest cleaner reaching to a place adjacent to said common discharge point, movable means operating beneath said point and a portion of said screen for removing refuse and dirt, and means associated with said discharge screens for withdrawing dust from the moss upon impact. 20
5. Apparatus of the character described comprising a primary cleaner for causing a preliminary separation of the refuse from moss, a curved screen against which the moss is discharged and spread, a finishing cleaner located below the primary cleaner, a chute
- located in common to both cleaners upon which refuse is discharged and gravitates to a common point, a bottom screen dividing the space between the curved screen and chute and upon which the moss gravitates to the finishing cleaner, the dirt falling through said screen into the chute, and a curved screen against which the moss is discharged from the finishing cleaner including a screen bottom portion extending to a place adjacent to the common refuse discharge point but not communicating therewith. 25
6. Apparatus of the character described comprising a primary cleaner, a curved screen against which moss is discharged, a finishing cleaner in a position below the primary cleaner, a bottom screen below the curved screen upon which the moss gravitates to the finishing cleaner, a curved screen against which the finishing cleaner discharges, a chute below the bottom screen and finishing cleaner upon which refuse falls and gravitates to a common point, a conveyor for carrying the refuse from said point, a bottom screen extending from the curved screen of the finishing cleaner partly situated above the conveyor so that dirt falling therethrough may reach the conveyor, said bottom screen forming part of a hopper, a dust extractor including a casing having a tight connection with the hopper, and an exhaust fan having connection with the casing for pneumatically transporting the moss from the bin to the dust extractor. 30
7. Apparatus of the character described comprising a primary cleaner, a curved screen against which moss is discharged, a finishing cleaner in a position below the primary cleaner, a bottom screen below the curved screen upon which the moss gravitates to the finishing cleaner, a curved screen against which the finishing cleaner discharges, a chute below the bottom screen and finishing cleaner upon which refuse falls and gravitates to a common point, a conveyor for carrying the refuse from said point, a bottom screen extending from the curved screen of the finishing cleaner partly situated above the conveyor so that dirt falling therethrough may reach the conveyor, said bottom screen forming part of a hopper, a dust extractor including a casing having a tight connection with the hopper, and an exhaust fan having connection with the casing for pneumatically transporting the moss from the bin to the dust extractor. 35
8. Apparatus of the character described comprising a primary cleaner having a feed table in the nature of a hopper into which rough moss is dumped, a curved screen against which the preliminarily treated

moss is discharged, a finishing cleaner having a movable feed table including a conveyor, a bottom screen below the curved screen upon which the moss slides by gravity to said conveyor and through which dust falls, a chute situated beneath the bottom screen and the finishing cleaner upon which refuse slides by gravity to a common point, a curved screen against which the moss is discharged from the finishing cleaner, said screen including an inclined and a horizontal portion defining part of a bin, a conveyor operating beneath said horizontal portion and said common point for disposing of refuse falling thereupon, a common outlet conduit having communication with each cleaner at the respective curved screens for exhausting dust, a dust extractor including a casing having a pipe connection with said bin, and an exhaust fan also having communication with said conduit and with said casing for pneumatically elevating moss from the bin to said casing.

9. Apparatus of the character described comprising a structure defining a chute converging toward a common point, a pair of false bottoms including screens situated at different places in said chute, a primary cleaner associated with the first screen discharging moss on top and refuse beneath, the movement of the moss over the screen causing a sifting action, a finishing cleaner receiving the moss from said screen and discharging the moss upon the second screen, refuse from the finishing cleaner falling into the chute and the movement of the moss over the second screen having a sifting action, means for removing the moss from said second screen to a place of final disposal, and means operating beneath said common point to continuously remove the refuse.

10. Apparatus of the character described comprising structure generally defining a chute, two hooded screens, a screen partition situated beneath each hooded screen, a primary cleaner associated with the first pair of hooded and partition screens discharging moss between the screens and refuse into the chute, a finishing cleaner receiving the moss from said screens and discharging it against the second pair of hooded and partition screens, the refuse falling through the chute, means continuously operating beneath the chute to remove the refuse including that produced by the sifting action of the moss upon said screens, and means associated with said hooded screens producing a suction to separate dust as the moss strikes said screens.

11. Apparatus of the character described including a building having ground, first and second floors, a primary moss cleaner situated on the second floor, a finishing cleaner situated on the first floor, means including an inclined screen upon which the

moss from the primary cleaner is discharged and gravitates to the finishing cleaner, means including an inclined screen upon which the moss of the finishing cleaner is discharged and gravitates toward the ground floor, a chute structure so arranged as to enclose said screens, receive siftings therefrom, and also the refuse from said cleaners, said chute also defining a bin on the ground floor, means continuously operating beneath the chute to remove the refuse, a dust extractor including a casing situated on the second floor having a pipe leading to the bin, and suction means having connection adjacent to the screens of each cleaner for separating dust from the moss and a connection with said casing for elevating the moss and also separating dust.

12. Apparatus of the character described comprising a cleaner having a rotatable toothed drum, a pair of rolls having upstanding intermeshing portions for introducing moss, a relatively stationary toothed element in respect to which the drum revolves, and means including a plate toward which the moss is worked and at which a separation of the refuse takes place.

13. Apparatus of the character described comprising a cleaner having a rotatable toothed drum, a pair of rolls having upstanding intermeshing portions for introducing moss, a relatively stationary toothed element in respect to which the drum revolves, means including a plate toward which the moss is worked and at which a separation of the refuse takes place, and means including a gear and rack arrangement for adjusting the plate to produce a proper separation of the refuse.

14. Apparatus of the character described comprising a moss cleaner having a rotatable toothed drum, moss feed means including a feed table, corrugated feed rolls for introducing moss from the feed means to the drum, a relatively stationary toothed member against which the drum operates, means for adjusting the position of said member in respect to the drum, a plate having a thickened leading edge at which a separation of refuse from the moss occurs, a chute into which the refuse falls, and a screen outlet into which the moss is discharged.

15. Apparatus of the character described comprising a dust extractor having a casing, a moss tube having a hood in communication with the casing, an exhaust fan having communication with the hood for drawing moss through the tube into the casing, a screen in the hood against which the moss is discharged causing it to fall into the casing, and a door at the outlet end of the casing held closed by the suction of the fan to receive moss.

16. Apparatus of the character described

comprising a dust extractor having a casing, a moss tube having a hood in communication with the casing, an exhaust fan having communication with the hood for drawing moss through the tube into the casing, a screen in the hood against which the moss is discharged causing it to fall into the casing, a door at the outlet end of the casing held

closed by the suction of the fan to receive moss, and means including a valve associated with the exhaust fan arranged to be opened to short circuit the fan and thereby permit the door to be opened by gravity for the dumping of the moss. 10

WESLEY DEUETTE TYLER.
